H. D. BARTLETT.

SOFA BED.

APPLICATION FILED JAN. 28, 1914.

1,108,858.

Patented Aug. 25, 1914.

UNITED STATES PATENT OFFICE.

HARRY D. BARTLETT, OF CHICAGO, ILLINOIS, ASSIGNOR TO PULLMAN COUCH COMPANY, OF CHICAGO, ILLINOIS, A CORPORATION OF ILLINOIS

SOFA-BED.

1,108,358.

Specification of Letters Patent. Patented Aug. 25, 1914.

Application filed January 28, 1914. Serial No. 814,917.

To all whom it may concern:

Be it known that I, HARRY D. BARTLETT, a citizen of the United States of America, and a resident of Chicago, county of Cook, 5 and State of Illinois, have invented certain new and useful Improvements in Sofa-Beds, of which the following is a specification:

This invention relates to convertible furniture of the class in which a series of foldably-related bed sections are arranged to unfold to form a bed, and more particularly to sofa beds in which means are provided for securing part of the sections in spaced folded relation while being unfolded or folded 15 with respect to the remaining section or sections. Beds of this character have been made in different ways, usually with the bed portion pivoted directly to the front of the sofa frame, or carried by a rotatably mounted hollow seat frame having a seat member for the sofa formed directly upon or carried by one side, and having the bed portion 20 pivotally connected to and carried by the reverse side, the bed in either case being 25 extensible transversely of the sofa and being foldable one section over another in the same direction for storage under the seat member when the bed is not in use.

The main objects of this invention are to 30 provide an improved form of fastening adapted for securing one or more of the sections in folded relation during the folding of the remaining sections; to provide an improved form of handle on the foot section 35 adapted for concealment normally and for ready movement into position when required to facilitate turning of said section; to provide improved locking means operable directly by said handle and adapted to secure 40 said foot section in spaced folded position and to provide an improved form of spacing latch and handle combined and adapted for operation by gravity.

An illustrative embodiment of this invention is shown in the accompanying drawings, in which:

Figure 1 is a side elevation of a sofa bed with the bed sections unfolded and with the near end of the sofa frame removed to 50 show the details of the seat member and operating member associated therewith. Fig.

2 is a similar view showing the bed in its folded position and with the seat frame ready for turning to its upright or normal sofa position. Fig. 3 is a side elevation of 55 the foot and middle sections of the bed illustrating the first stage of the unfolding operation with the foot section locked in spaced folded relation upon the middle section and disposed in an upright position. Fig. 4 is 60 a side view similar to Fig. 3 but illustrating the next stage of unfolding, the middle section being in its bed position and the foot section being folded thereupon. This view also shows in dotted lines the succeeding vertical position assumed by the foot section as it swings outward. Fig. 5 is a broken plan view of a portion of the bed bottom when extended, and shows the relative position of the leg folding and section locking members 65 on one side of the bed. Fig. 6 is a perspective view of the combined handle and locking members.

In the construction shown in the drawings, the sofa bed comprises the usual housing or frame 1 having ends 2 and back 3 in combination with a rotary seat frame 4 operatively mounted between and supported by the ends 2. This seat frame on one side is adapted to serve as a seat 5, and the reverse side is formed as a hollow frame adapted and arranged to support the bed sections pivotally attached thereto for unfolding when the seat frame 4 is turned to its inverted position, as shown in Fig. 2. 75 The connection of the seat frame 4 to the sofa frame 1 may comprise any of the means well known in the art, as plates 6 and 7.

The bed bottom or frame 12 comprises 80 three wide major sections 14, 15 and 16 and two narrow minor sections 17 and 18 suitably hinged together, as by rule joints, in alternate position. These sections are adapted to be folded together upon the under side 85 of and within the seat frame 4, with the three major sections lying substantially in horizontal position and with the minor sections vertically disposed at the opposite edges thereof.

Bed supporting brackets 19 are secured to 90 the ends of the seat frame 4 adjacent to

that edge of the seat frame which is in front when in the bed position. The outer and upper ends of these brackets are formed and adapted, as at 20, to receive the pivot members 21 secured to the sides of the narrow bed section 17 intermediate of the ends thereof. The section 17 thus mounted is adapted to swing from a vertical storage position to a horizontal bed position. The head section 14 and the middle section 15 are hinged to the section 17 at opposite ends thereof, lower and upper respectively when folded.

The head section 14 is raised and lowered in its horizontal position within the seat frame with the shifting of the narrow section 17 to and from its horizontal position respectively, by means of plates 22 located rearwardly of the brackets 19 and adjacent to the ends of the seat frame 4. Each plate 22 is formed with a rearwardly inclined forward surface 23 on which slide the studs or shoulders 24 secured to the section 14, each of which surfaces 23 terminates at its upper end in a horizontal surface 25 on which the studs 24 rest when the section 14 is shifted to its elevated or bed position, and at its lower end terminates in a socket 26 which coacts with its respective stud 24 for securing the section 14 in its lowered position.

The foot minor section 18 and the foot major section 16 are hinged together, and the former is hinged to the middle major section 15. Sections 16 and 18 are adapted to be extended in horizontal alinement, or to be folded with section 15 upon the seat frame with the foot section 16 between the sections 14 and 15. The head and middle major sections may be of substantially the same length, but the foot section 16 is somewhat shorter so that it may be folded between the longer sections, the difference in length being substantially equal to the thickness of the mattress and usual bedding (not shown). The short sections 17 and 18 are also of different lengths, the difference being a little more than the thickness of the mattress and bedding.

The outwardly disposed sections are supported in their bed position by means of legs 29 and 30 pivoted at 31 and 32 to the outer ends of sections 15 and 16 respectively. These legs are automatically controlled by means of links 33 and 34 respectively as will be understood. The short foot section 18 is braced by a rod 35 connected at its ends to the medial portions of the sides, preferably at the pivotal connection of the links 34.

Improved means are provided for securing the foot section 16 in folded relation upon the adjacent major section 15, said means comprising a combined latch and handle member 36 pivoted to the outer end of the foot section and adapted to swing freely in parallel with the section folding

movement through its range of operation, 65 the planes of movement all being transverse of the hinges, and in this instance parallel with the length of the bed. The said latch and handle member comprises an axial portion 37 adapted for pivotal support at its 70 ends upon the sides of section 16 and a pair of parallel latch portions 38 disposed transversely thereto, the axial portion also having a handle part 39 disposed laterally from the axis, and at an angle from said latch portions, said angle being preferably about 90 degrees, or somewhat greater. This member 36 is adapted to be held normally by gravity with the handle portion 39 projecting downward and the latch portion horizontally 80 when the bed is unfolded, and is also adapted to turn when the outer section 16 is folded upon the inner section 15 so that the latch portions will project downward for engagement with the sides of section 15 to secure 85 said sections locked together, and with said handle part disposed horizontally upon the bed spring 40. The handle portion 39 is relatively heavy and acts by gravity to dominate the swinging of the member 36. 90

The middle section 15 is provided on its sides with coacting means adapted for locking engagement with the latch members 38, said means on each side comprising a stud or shoulder 41 fixed on said inner section 95 and a resilient yielding member 42 also secured thereto adjacent to said stud for urging the adjacent latch into engagement therewith and yieldably holding the same in engagement. 100

The free or downwardly facing end of each latch 38 is broad and formed with a V-shaped notch between two divergent arms 45 and 46 adapted to guide the latch and the coacting stud into engagement. At the inner end of the notch a catch shoulder or hook 48 is provided on one of the arms 45 adapted to engage the stud 41 to prevent separation. The spring 42 operates to urge the latch hook 48 into engagement with the 110 stud 41. The tip of the hook 48 inclines somewhat toward the pivot so that when locked the expansive pressure of the bedding tends to prevent disengagement of the stud therefrom independently of spring 42. 115

The operation for unfolding the bed is as follows: The seat frame is inverted from its sofa position and the bed sections are then unfolded to the position shown in Fig. 4. The latch handle is then grasped and raised 120 from the bed spring, thereby disengaging the latches from the middle section, said handle being used also if desired, for swinging the foot section into its bed position, whereupon the hand is released and the handle is swung 125 by gravity to a substantially concealed position beneath the foot section, and the latch members being swung thereby to a horizon-

tal position parallel with the sides of the foot section.

The folding operation is as follows: The depending handle 39 may be grasped and 5 swung to project rearwardly from under the foot section, whereby it serves as a convenient means for lifting said section for folding it upon the middle section. As the foot section swings downward into place the 10 said handle is swung back toward the operator and downward to rest upon the bed spring, and the latch members swing to a downwardly projecting position and into co-action with the fastening means on the middle section, whereby said sections are secured in spaced folded relation. If preferred, the foot section may be lifted by grasping the foot rail instead of the handle, in which case gravity will cause the latch 15 and handle member to rotate to bring the latches into their operative downward position for engaging the middle section, as above indicated. When the latches are thus engaged the foot and middle sections may be 20 swung as a unit to fold upon the head section, whereupon the seat frame is turned to 25 its normal sofa position.

Although but one specific embodiment of this invention has been herein shown and described, it will be understood that numerous 30 details of the construction shown may be altered or omitted without departing from the spirit of this invention as defined by the following claims.

35 I claim:

1. In a device of the class described, a plurality of bed sections adapted to fold together, in combination with a handle pivoted to the outer end of the outermost section and 40 adapted to be swung by gravity beneath said section when the bed is unfolded and to be swung outwardly manually to serve as a section-lifting handle for manipulating the bed, said handle having a latch member 45 carried thereby for turning therewith and adapted to engage an inner section when the said outer section is folded thereupon.

2. In a device of the class described, a plurality of bed sections adapted to fold together, in combination with a medially disposed handle pivoted to the outer end of the outermost section and adapted to be 50 swung by gravity beneath said section when the bed is unfolded and to be swung outward manually to serve as a handle for manipulating the bed, said handle having latch members carried thereby and secured rigidly thereto one at each end thereof and adapted 55 to engage the sides of an inner section when the said outer section is folded thereupon, said latch members being disengageable by lifting on said handle in unfolding the bed.

3. In a device of the class described, a plurality of bed sections adapted to fold to-

gether, and a combined latch and handle 65 member of unitary character pivoted to the outer section for swinging freely in parallel with the folding movement through its range of operation, said latch and handle member being formed at an angle and adapted normally to be held by gravity with the handle portion projecting downward and the latch portion horizontally when the bed is unfolded and to turn upon said outer section by gravity when the same is folded upon an inner section so that the latch member will project downward for engagement with said inner section to secure said sections locked together and with the handle member disposed horizontally upon said outer section. 70 75 80

4. In a device of the class described, a plurality of bed sections having a bed spring carried thereby and adapted to fold together, and a combined latch and handle member of unitary character pivoted to the outer section for swinging freely in parallel with the folding movement through its range of operation, said latch and handle member comprising an axial portion adapted for pivotal support at its ends upon the sides of 85 90 said outer section, and a pair of parallel latch portions disposed transversely thereto, the axial portion also having a handle part laterally disposed from the axis thereof at an angle from said latch portions, said latch 95 and handle parts being adapted normally to be held by gravity with the handle portion projecting downward and the latch portion horizontally when the bed is unfolded and to turn when said outer section is folded 100 upon an inner section so that the latch portions will project downward for engagement with the sides of said inner section to secure said sections locked together and with said handle part disposed horizontally upon 105 the bed spring.

5. In a device of the class described, a combined latch and handle member of unitary character comprising an axial portion formed and adapted for pivotal support at 110 points spaced apart and including a handle disposed at one side of the axis between the bearing points, and a pair of latch portions spaced apart and carried by opposite ends of said axial portion adjacent to the bearing 115 points and disposed in a plane at an angle from said handle, said handle being relatively heavy with respect to the latch portions and being adapted for actuation by gravity to swing downward and hold the 120 latch portions substantially horizontal.

6. In a device of the class described, a plurality of bed sections adapted to fold together, in combination with a latch pivoted to the outermost section, and means on an 125 inner section adapted for locking engagement with said latch member, said means comprising a stud fixed on said inner sec-

tion and a resilient yielding member secured to said inner section adjacent to said stud but spaced therefrom to receive the latch therebetween, said member being adapted for urging the latch into engagement with said stud and yieldably holding the same in engagement.

Signed at Chicago this 26th day of January 1914.
